ABSTRACT

A fuel oil vaporizer for separating the volatile components from the nonvolatile components and feeding the volatile components to the inlet manifold of a diesel engine thus permitting the use of low-grade fuel oils in diesel engines.

OIL VAPORIZER

BACKGROUND OF THE INVENTION

The present invention is directed to fuel oil vaporizers and in particular to fuel oil vaporizers for use in association with diesel engines.

At the present time the lower grades of fuel oil cannot be used with diesel engines. Such oils contain substantial amounts of nonvolatile and noncombustible materials which, if fed into the cylinder of an internal combustion engine, would cause excessive wear and greatly increased operational costs.

The lower grades of fuel oil, such as bunker "C," cost considerably less than the refined grades. The economic advantages which could be obtained from the use of such lower grades of fuel oil in internal combustion engines are quite impressive.

GENERAL DESCRIPTION OF THE INVENTION

It is therefore an object of the present invention to provide a process for removing the nonvolatiles and noncombustibles from low-grade fuel oils so that these fuels would be suitable for use in internal combustion engines.

Accordingly there is provided a process for vaporizing fuel oil which comprises a spraying a fuel oil containing volatile and nonvolatile components from a spray means so that the oil impinges on a heated surface causing the volatile component in the fuel oil to vaporize. The vaporized volatile component of the fuel oil is then conveyed away from the area adjacent to the spray means and the residue comprising the nonvolatile component of the fuel oil is collected and removed from the area adjacent to the spray means.

There is also provided a vaporizer for fuel oil which comprises a vessel having a heated surface, spray means adapted to spray fuel oil on said heated surface, heater means located exteriorly of said vessel to heat said surface sufficiently to vaporize said fuel oil spray, a vapor outlet from said vessel, and scraper means at the base of said vessel to collect the nonvolatile residue from said oil spray.

SUMMARY OF THE DRAWINGS

The following is a description by way of example of certain embodiments of the present invention reference being had to the accompanying drawings in which:

FIG. 1 is a vertical section of a fuel vaporizer of the present invention;

FIG. 2 is a vertical section of a larger and more complex vaporizer of the present invention;

FIG. 3 is an elevation of the vaporizer used in association with a diesel engine.

DETAILED DESCRIPTION OF THE INVENTION WITH REFERENCE TO THE DRAWINGS

Referring to the vaporizer illustrated in FIG. 1, during start up of this unit, propane gas is injected through the fuel tube 11 to the burner ring 12. Combustion air is introduced through the air tube 13 to air defuser ring 14 which is located beneath the burner ring 12 and has openings on its upper surface to distribute the combustion air. The gas/air mixture is ignited above the burner 12 by means of an electrical spark plug which is not shown. Combustion takes place between the combustion cylinder 15 and vaporizing cylinder 16. Heat transferred by conduction then raises the temperature of the vaporizing cylinder 16 to its operational temperature. The combustion gases are vented to the atmosphere through the side outlet 17 near the top of cylinder 15.

When the vaporizing cylinder 16 has reached its operational temperature as indicated for example by a pyrometer sensing at the vaporizing area on the inside of cylinder 16 the operator may then cause fuel oil, preheated to approximately 190° F., to be introduced to the spray nozzle 18 located centrally in the base of cylinder 16. As the preheated fuel oil leaves the spray

nozzle 18 it impinges on the heated cylinder 16. This metal cylinder 16 is heated to a temperature sufficient to vaporize the fuel oil. It has been found that a temperature of approximately 1,000° C. is satisfactory for a lower grade of fuel oil such as bunker "C." The nonvolatile and noncombustible solid ash released during the vaporization phase falls to the base of cylinder 16 where rotating scraper device 19, driven by gear 50 and drive shaft 51, collects it along the circular base plate 20 and causes it to fall through a discharge port at ash hole 21. At this point it may be collected in a sealed container, which is not shown, for periodic removal.

After the initial vaporization on the sidewalls of cylinder 16 the fuel vapor passes up the vaporizing cylinder 16 picking up additional heat from the cylinder walls and then leaves through the manifold port 22 to enter the supply manifold 23.

With the supply manifold now at operation pressure, the operator may "bleed off" a sufficient portion of the vapor from the manifold 23 to the burner ring 12 to replace and eliminate the use of the propane required at start up. This changeover from propane to vapor may be accomplished through automatic controls that simultaneously reduce the propane flow while increasing the oil vapor flow to the burner ring 12. Further, the vapor may pass through a pressure reducing valve arrangement to reduce the vapor manifold pressure to that of the propane.

A somewhat larger and more complex vaporizer is illustrated in FIGS. 2 and 3. The operation of this vaporizer is as follows.

To start up the vaporizer, propane gas is injected into the flame tube 30 and through to the burner 31. Combustion air is introduced into the air tube 32 which surrounds flame tube 30. The gas/air mixture is ignited above the burner 31 by means of an electrical spark plug 33. Combustion takes place in cylinder 34 which raises the temperature of the vaporizing cylinder composed of lower cylinder 35, transition piece 36, and upper cylinder 37 to an operational temperature which is sufficiently high to vaporize the fuel oil. In practice a temperature of approximately 1,000° F. has been found to be satisfactory for this purpose. After combustion the combustion gases are vented to the atmosphere through the top of cylinder 34.

When the vaporizing cylinder 35 has reached its operational temperature as indicated for example by a pyrometer sensing at the vaporizing cylinder 35 the operator may cause the fuel oil preheated to approximately 180° F. to be introduced into one or all of the spray nozzles 38. When the demand for vaporized oil is low, one nozzle operating may be sufficient.

As the oil leaves the nozzle head 38 and impinges on the heated cylinder 35 it is vaporized. The nonvolatile and noncombustible material released during vaporization falls to the base cylinder 35 where a rotating scraper device 44 collects it along circular base plate 39 and causes it to fall through a port discharging at ash hole 40. At this point it may be collected in a container, which is not shown, for periodic removal.

After the initial vaporization in cylinder 35 the vapor passes through a louvred vapor screen 41 and travels upwardly through the space between the combustion cylinder 34 and upper vaporizing cylinder 37 where it picks up additional heat. This heat transferred to the vapor may be increased by incorporating fins or pins or some such other device into the walls of the combustion cylinder 34. The vaporized fuel oil continues on through header 42 at approximately 1,000° F. to the manifold 43.

The pressure in the cylinder 35 can, of course, be quite high and a pressure of 600 to 1,000 p.s.i. has been found to give excellent results. At this pressure and operating at a temperature of about 1,000° F., the fuel oil is vaporized to give a vapor having a density of about 60 percent that of the liquid fuel oil.

As the vapor collects and pressure is built up within the vaporizing cylinder 37, the pressure at the spray nozzle 38 is increased accordingly. Modulating type controls may be used to maintain this pressure throughout the operating cycle of the vaporizer.

With the manifold 43 now at operational pressure the operator may "bleed off" a sufficient portion of the vapor from the manifold 43, via pipe 57 shown in FIG. 3, to the flame tube 30 to replace and eliminate the propane required at start up. This changeover from propane to vapor may be accomplished through automatic control valve 58 that would simultaneously reduce the propane flow while increasing the vapor flow to the flame tube 30. Further, the vapor passes through a pressure reducing valve arrangement 59 which reduces the vapor manifold pressure to that of the propane. Now that changeover is complete the vaporizer is fully operational.

FIG. 3 illustrates the vaporizer when operated in association with a diesel engine, the engine being controlled from the normal existing throttle and governor.

Studying this figure it will be seen that the propane is fed to the vaporizer 51 by pipe 52. The fuel oil is fed from the fuel oil tank 53 via pipes 54 to the nozzles 38. The vaporized fuel oil leaves from the top of the vaporizer, travels along manifold 43 through pipe 55 to the diesel engine 56. When the vaporizer is at operational temperature vaporized fuel oil is bled off from the manifold 43 through pipe 57 to valve 58 on the propane line 52. Thus it is possible to gradually reduce the flow of propane and finally operate exclusively on fuel oil.

A decrease in manifold pressure activates automatic external controls to compensate for this loss by modulating fuel oil flow to the nozzle 38 and thus restore and maintain the operating manifold pressure. Depending on operation requirements of the engine, one or more or all of the nozzles 38 may be in operation at any one time.

The principle of prevaporation of the fuel, the extraction of the nonvolatile and noncombustibles externally of the engine cylinder and the injection of vapor instead of atomized fuel into the cylinder of the engine assures a more complete combustion and smokeless operation of the unit.

Further, adapting the vaporizer unit to an existing diesel engine requires no extensive modifications to the diesel engine itself. Basically adaption of an existing diesel engine is achieved by removing the existing fuel oil lines and installing gas lines to the new vapor supply manifold which in turn is connected to the discharge port of the vaporizer unit.

Inasmuch as the vapor is delivered to the engine at approximately 1,000° temperature and approximately 600 p.s.i., the fuel pump will, as before, meter the gas to the injector. However, since volume of the vapor is approximately 0.97 cu. ft. per imp. gallon of oil vaporized, the injector capacity may need to be increased as fuel requirements of the engine dictate.

I claim:

1. In a vaporizer for fuel oil containing volatile and non-volatile components, the combination of a vertically elongated vaporizing chamber defined by at least one substantially cylind-

rical wall, means for heating said wall, means provided in the lower portion of said chamber for spraying fuel oil onto the heated wall so that volatile components of the oil are vaporized and rise in the chamber while nonvolatile components fall as residue to the bottom of the chamber, said chamber having an outlet at the top thereof for the vaporized volatile components, and disposal means at the bottom of the chamber for removing the residue therefrom.

2. The device as defined in claim 1 together with a second substantially cylindrical wall surrounding the first mentioned wall in spaced relation, said first and second walls defining a heating chamber therebetween, said vaporizing chamber existing within the first wall and the oil spraying means in the vaporizing chamber being adapted to spray oil onto the inner 15 surface of the first wall, said heating means being disposed in said heating chamber for heating the outer surface of the first wall.

3. The device as defined in claim 1 together with a second substantially cylindrical wall surrounding the first mentioned 20 wall in spaced relation, said first and second walls defining a heating chamber therebetween, said first wall defining a heating chamber therewithin, said oil spraying means in the vaporizing chamber being adapted to spray oil onto the outer surface of the first wall, and said heating means being disposed 25 in said heating chamber for heating the inner surface of the first wall.

4. The device as defined in claim 1 wherein said oil spraying means comprise at least one spray nozzle.

5. The device as defined in claim 1 wherein said heating 30 means comprise a gas burner.

6. The device as defined in claim 1 wherein said heating means comprise a gas burner, together with means for supplying fuel to said burner from said outlet of vaporized volatile components.

35 7. A process for vaporizing fuel oil containing volatile and nonvolatile components, comprising the steps of (a) heating a wall of a vertically elongated vaporizing chamber, (b) spraying fuel oil onto the heated wall so that volatile components of the oil are vaporized and rise in the vaporizing chamber while 40 nonvolatile components fall as residue to the bottom of the chamber, (c) withdrawing the vaporized volatile components from the top of the chamber, and (d) removing the residue from the bottom of the chamber.

8. The process as defined in claim 7 which is further characterized in that the vaporizing chamber wall is heated from one side and the fuel oil is sprayed on the opposite side of the wall.

9. The process as defined in claim 7 which is further characterized in that the vaporizing chamber wall is heated by a gas burner, together with the additional step of utilizing a portion 50 of the vaporized volatile components withdrawn from said chamber as fuel for said gas burner.
